UNITED STATES PATENT OFFICE.

ALBERT V. T. DAY, OF NEW ROCHELLE, NEW YORK, ASSIGNEE, BY MESNE ASSIGNMENTS, TO HALL SWITCH & SIGNAL COMPANY, OF NEW YORK, N. Y., A CORPORATION OF MAINE.

RAILWAY SIGNALING SYSTEM.

1,099,283.

Specification of Letters Patent. Patented June 9, 1914.

Application filed August 28, 1908. Serial No. 450,716.

To all whom it may concern:

Be it known that I, ALBERT V. T. DAY, a citizen of the United States, residing at New Rochelle, in the county of Westchester and State of New York, have invented a certain new and useful Improvement in Railway Signaling Systems, of which the following is a specification, reference being had therein to the accompanying drawings, forming part thereof.

My invention relates to electric traffic-controlling systems and apparatus for railways, and the object of the invention, generally stated, is to produce a traffic-controlling system which shall be simple and reliable in operation, and economical in material and in expenditure of energy.

While my invention is applicable, in general, to systems of various kinds, for the operation of various traffic-controlling devices, such as automatic train-stopping devices, switches, cab signals, etc., it is particularly applicable, in some of its features, to automatic systems for controlling visual signals such as semaphores.

My invention is particularly illustrated and described as embodied in a signal-controlling system of the type characterized by the use of track relays selectively responsive to periodic currents of different frequencies, together with means for feeding currents of different frequencies at different points in the track rails. In another application filed of even date herewith, Serial Number 450,715 I have described an improved system of this type in which electrically independent generators are employed for feeding the track rails, in order to prevent the interchange of stray currents of different frequencies between the several feeding points. In my present invention, I make use of this arrangement, and one object of my invention is to provide the system with improved means for actuating the track generators.

In the present invention, as in the system disclosed in my application hereinbefore referred to, the relays are rendered selectively responsive to currents of particular frequencies by providing them with fields energized by currents of corresponding frequencies and of suitable phase relation; and a second object of the present invention is to provide improved means for supplying the currents for energizing the relay fields.

My invention is particularly illustrated as embodied in a system comprising both home and distant signals, and provided with traction current conductors for the operation of electric cars or trains, and further objects of the invention are, in such connection, to economize in the use of conductors in the various line and transmission circuits, and in the use of generators for energizing the signal-controlling apparatus and for supplying traction current by combining several functions, where possible in one conductor or generator, through the use of novel apparatus and arrangements herein-after described.

Other objects of the invention will be set forth in connection with the following specific description and my invention consists in the traffic-controlling system hereinafter described and illustrated in the accompanying drawings, as defined in the succeeding claims.

I will now describe the illustrated embodiment of my invention, and will thereafter point out the invention in claims.

The drawing illustrates diagrammatically a portion of a railroad track equipped with an automatic electric signal-controlling system embodying the present invention, and it shows two complete blocks and portions of two others.

In the drawings and the following description the track is considered as divided into blocks beginning and ending with the successive signals, and the blocks are designated successively as A, B, C, etc. The apparatus pertaining to each block includes the signals at the entrance to the block, the relays and other apparatus directly connected with these signals and located thereat, the track relays located at the middle of the block, and the generator set by which current is supplied for the feeding point near the entrance to the block. The apparatus in the several blocks is identical in general construction, and corresponding parts in the several blocks are designated, in general, with the same reference numbers, but in the following description these numbers are followed where necessary, by the letters A, B and C, to indicate in which block the particular part in question is located.

The railroad track of the drawing comprises rails 15 and 16 which are bonded or

otherwise rendered continuously conductive throughout. The trains move from east to west or in the direction of the arrow 1, a home signal, 2 and a distant signal 3 are located at the entrance of each block, and the signals of each block are electrically controlled by two track relays 4 and 5 connected across the track rails at or near the middle of the block.

10 The relays are of the polarized alternating current type. The relay 4 has a field magnet 6 which is constantly energized by alternating current, and a pivoted armature 7 which is provided with a coil and carries a 15 contact finger 8 coöperating with a fixed contact 9. The relay 5 is similar in all respects to the relay 4 except that its contact finger coöperates with two fixed contacts 10 and 11, whereby it is constituted a pole-changing relay, and its field is energized with alternating current of different frequency from that in the field of the relay 4.

The armature coils of the relays are connected in parallel, by wires 12, across the 25 track rails at points 13 and 14. The construction of the relays is such that currents passing through the armature coil do not affect the armature and actuate the relays unless they are of the frequencies employed 30 in energizing the field magnets and are also in suitable phase relation therewith. The relays thus act selectively, responding only to certain currents flowing through the track rails.

35 The track rails act as conductors for signal-controlling currents and form portions of train-controlled circuits. At a point near the entrance of each block an alternating generator 20 is connected, through wires 29 40 across the rails. The points of connection are designated successively by the reference numbers 17, 18, and 19 and are hereinafter called "feed points". The alternating current produced by the generator 20 A flows, 45 from the feed point 17, through the rails and through the wires 12 and the armature coils of the track relays 4 and 5 A. The current from the generator 20 B also flows, from the feed point 18, to and through the relays 50 4 and 5 A, and it flows likewise to and through the relays 4 and 5 B. The same thing occurs at C, the current flowing from the feed point 19 to the relays at B and the relays (not shown) at C.

55 All of the generators 20 at A, B and C are constructed to produce currents of different frequencies. These generators are of the ordinary type in which the frequency is determined by the form of the field and the 60 speed of the armature. Their fields 21 are energized with constant current through a wire 23 from a transmission line wire 57. The transmission line is fed, through a wire 22 from a generator 24, and the track rails 65 are utilized as a return conductor. To pre-

vent short-circuiting of the signal-controlling apparatus connected with the rails, the generator 24 is connected with the two rails through a balanced choking coil 25, which acts to impede the flow of alternating current from rail to rail while permitting parallel and equal currents in its two halves to pass freely.

Each generator 20 is actuated by a motor 26. In order to determine accurately the 75 relative speeds of the several generators 20, the motors 26 are of the synchronous alternating current type, and their armatures are energized by connection through a wire 31 with a transmission line conductor 56. The conductor 56 is fed, through a wire 30 by an alternating current generator 32, and the track rails are utilized as return conductors for this current also, the generator 32 being grounded through the choking coil 25. 80 The field 27 of the motor 26 is connected in series with the field of the generator 20, so as to be energized by direct current from the wire 22.

Each generator set includes a generator 35 90 which supplies current to energize the field of the track relay 4 of the same block and the field of the track relay 5 of the next block to the east. The generator 35 is of the same construction as its companion generator 20 and furnishes current, in each case of the same frequency, but the two generators of each set are electrically independent so that no interchange of alternating currents can occur between them. The field 36 100 of the generator 35 is connected in series with the fields 21 and 27 so as to be energized by constant current from the wire 23. The three fields and the armature of the motor 26 all have a common return through 105 a wire 28 and one of the wires 29 to one of the rails. At alternate stations these common returns are connected to opposite rails so as to distribute the currents equally between the rails.

The several currents of different frequencies used in this system will be, for convenience, referred to as currents of *a* frequency, *b* frequency, etc., to distinguish them, and on the drawings the letters, *a*, *b*, etc. are applied at various points to indicate the currents present or effective at such points. In order that the alternating current from the generator 32 may not interfere with the operation of the track relays this current is of 115 a substantially different frequency from that generated by either of the track generators, and is designated by the letter *d*.

Currents of three frequencies, *a*, *b*, and *c*, 120 are generated by the generators 20, these frequencies being used in their alphabetical order throughout the system, beginning at block A.

The current for energizing the field of the relay 4 of each block is conducted from the 130

generator 35, through wires 34 to line wires 33. The line wires are connected through a condenser 37, with the field magnet 6. The condenser is in resonance with the current from the generator 35 so as not to obstruct the energization of the field and it is used to prevent the passage of direct current through the field, for a purpose hereinafter described.

Since the field of the relay 4 is energized constantly with current of the same frequency as that of the current fed to the rails at the eastern end of the block, the relay is responsive to the latter current, and its armature thus acts normally to maintain the contact finger 8 in engagement with the fixed contact 9. Thus, in the block B, the field of the relay 4 B is energized by current of *b* frequency, while its armature is energized by current of *b* frequency, flowing from the generator 20 B, through the wires 29 B and the track rails.

The field of the relay 5 A is also energized by current of *b* frequency. The line wires 33 constitute part of a line circuit passing from one signal station to the next station to the east. They are connected with the contact fingers of a pole-changing switch 40 which is mechanically connected with the home signal 2, so as to be raised and lowered thereby. The fixed contacts of the switch 40 are connected through wires 38 and a condenser 39 with the field magnet of the relay 5. The condenser 39 is similar in purpose and character to the condenser 37.

The fields of the relay 4 of one station and of the relay 5 of the next station to the east are thus constantly energized by current of the same frequency and from the same source, and by current of the same frequency as that fed to the rails at the intermediate feeding point. In the case of the relay 5, however, the phase of this current is subject to reversal by the pole-changing switch 40, and according to the position of this switch the contact finger of the relay 5 will be moved to engage its contact 10 or the opposite contact 11. In the normal position of the apparatus the contact 10 is engaged.

The signals 2 and 3 may be ordinary semaphores, actuated by electrically-controlled mechanism of any ordinary or suitable form. As shown, they have a bias to danger position, but are held normally clear by their actuating mechanism, the latter being maintained in operation by a normally closed local signal circuit. The selective operation of the two signals, by which either the home signal or both the home signal, and the distant signal may be cleared is controlled by a polarized signal relay 45, and this relay is controlled, in turn, by current from the pole-changing track relay 5 of the next station to the west.

The relay 45 has a contact finger 46 which

engages a fixed contact 47 when moved to the right, and two contacts 48 and 49, when moved to the left. A signal battery 53 is connected with the contact finger 46. When the contact 47 is engaged current from the 70 battery flows through a wire 50 to the home signal 2 and thence, by a common return wire 52, back to the battery. Under these circumstances the home signal 2 alone is cleared. Normally the contacts 48 and 49 75 are engaged, and current flows through both wires 50 and 51 to clear both signals.

The direct currents by which the signal relay 45 is controlled are transmitted through the line wires 33, which serve as common 80 conductors, therefore, both for this current and for the alternating current to energize the track relays. These direct currents are furnished by two batteries 41 and 42, which are connected respectively with the fixed 85 contacts 10 and 11 of the relay 5, and are also connected by a common wire 64, with the upper one of the wires 33. The contact finger of the relay 5 is connected by a wire 43 with the contact finger of the relay 4, and 90 the fixed contact 9 of the relay 4 is connected, by a wire 44 with the lower wire 33.

By the conjoint action of the track relays 4 and 5 a circuit is closed including one of the batteries 41 and 42, the contact fingers and fixed contact fingers of the track relays, the wires 33 and the magnet of the signal relay 45. The arrangement of the batteries 41 and 42, as shown in the drawing is such that according to the position of the 100 contact finger of the relay 5 either the one or the other battery is thrown into operation, and the two batteries are so connected as to produce currents of opposite polarity. In this manner the movement of the contact 105 finger 46 of the signal relay to right or left is controlled by the track relay 5. The latter is controlled, however, by the pole-changing switch 40 as above described, and the pole-changing switch is moved by the home 110 signal 2. From this general arrangement it results, therefore, that each signal relay is controlled according to the position of the home signal of the next block in advance or to the west, so that the distant signal may 115 or may not be cleared with the accompanying home signal according as the home signal at the next block in advance is or is not clear.

The condensers 37 and 39 have their 120 utility in connection with the arrangements just described, since they prevent the field coils of the track relays from acting as short circuits for the direct currents from the batteries 41 and 42. For a similar purpose, condensers are included in the connections between the generators 35 and the wires 33. In order to prevent the direct current apparatus, from acting, on the other hand, to short circuit the alternating cur- 125

rent from the generator 35, choking coils 54 and 55 are interposed in the two direct-current branches of the line circuit occupied by the signal relay and by the batteries. 5 The magnets of the relays 45 are also provided with copper sleeves 66 surrounding their cores, to preclude the possibility of the relays being affected by such alternating current as may be forced through the choking coils 54.

10 The hereinbefore described signal controlling apparatus is of such construction as not to interfere with the use of the track rails as return conductors for traction current, 15 and the illustrated railway is shown as being arranged for electric traction. For this purpose, I propose to use, as conductors for traction current, either or both of the transmission line wires 56 and 57, the current 20 being furnished by the generators 24 and 32. The two conductors are shown in the drawings, as constituting respectively a third-rail and a trolley wire. The train or car, indicated diagrammatically at 60, may be 25 provided with a contact member or shoe 61 engaging the third rail 56 and a contact member or trolley wheel 62 engaging the trolley wire 57, and these contact members may be used either alone or, as is the practice on some railways, alternatively in different parts of the road. The direct current from the generator 24 obviously will not interfere with the operation of the track relays, while the alternating current from 30 the generator 32 of frequency d , cannot actuate the relays since they are selectively sensitized to currents only of a , b , and c frequency. By the above described arrangement, I greatly simplify the railway system 35 as a whole, and economize in the use of conductors and generators.

40 The operation of the signal-controlling apparatus as a whole will now be described.

With the blocks A and B clear the signals 45 at A are both clear, as illustrated. Suppose, however, there be a train or a car in block B. The wheels and axles of the train or car act as conductors between the rails and afford a path of such low resistance for the 50 current flowing from the nearest feeding point that they substantially delimit the transmission of such current in the rails. In this manner either or both of the armatures of the track relays in the block B will be 55 short-circuited, according to the position of the train in the block. If, for example, the train be between the points 14 and 18, the relay 4 B will receive no current from the feed point 18, and its contact finger will be 60 released and disengaged from its fixed contact, for the current of c frequency flowing to the relays 4 and 5 from the feed point 19 is not of proper frequency to actuate the relay 4.

65 It is true that some current of b frequency

may still find its way to the relay 4 B from a feed point two and one-half blocks in advance of the train, but this current will be very feeble, owing to the impedance of the intervening length of rails through which it is transmitted, and the relay is adjusted so as not to respond to such feeble currents.

70 In any case one of the relays 4 or 5 B acts to open the circuit connecting the battery 41 B with the signal relay 45 B, and the latter thereupon is deenergized and opens the signal circuit through both signals 2 and 3 B, so that they both go to danger position. The distant signal 3 A also goes to danger position at the same time, through 75 the action of the home signal 2 B upon the pole-changing switch 40. This switch being reversed by the movement of the signal 2 B, the alternating current flowing from the generator 35 B to the field magnet of the relay 5 A is reversed in phase, and the contact finger of this relay thereupon moves from the fixed contact 10 to the fixed contact 11. The battery 41 A is thereby cut out and the battery 42 A cut in, the direct current in the line circuit and the signal relay 45 A is reversed, the contact finger 46 moves from the fixed contacts 48 and 49 to the fixed contact 47, and the distant signal 3 A, being thus deenergized, rises to danger position, indicating an obstruction in block B.

80 The breaking of a rail at any point in the system operates, with the same effect as the presence of a train, to intercept the current by which one or another of the track 85 relays is actuated, thereby causing the signals to be set to danger position.

85 Although the feeding points 17, 18, 19, etc. are located approximately at the entrance ends of their respective blocks, they 90 are located slightly in advance of the corresponding signals. This is necessary to prevent the movement of the signals to danger position until the train or car has reached or passed them. As the train or car approaches the feed point and shortens the length of intervening rails, a point is finally 95 reached, at a short distance from the feed point, at which the impedance of the rails and the wheels and axles becomes so slight 100 that substantially the whole of the current from the feed point is diverted from the relay 4 at the middle of the block, so that this relay is rendered inactive before the train has entered the block. The signal is therefore located at or in the rear of this critical point, so that it shall be reached or passed 105 before the above described action occurs.

110 The various features of arrangement hereinbefore described are such as to effect great 115 economy in apparatus and the number of wires employed. Among these features may be pointed out particularly for use of motors energized from one point, through 120 transmission lines, for generating the cur- 125

rents employed at the several blocks, the use of a single constant-current generator for energizing the fields of all the local generators and motors and for furnishing traction current, the use of a common conductor—the track rails—in both transmission lines, and the use of the same line wires for both the alternating currents to energize the relay fields and the direct currents to control 10 the signal relays.

Various modifications may be made in the embodiment of my invention hereinbefore described and illustrated in the accompanying drawing, within the nature of the invention and the scope of the following

claims:

I claim:

1. A traffic-controlling system comprising track rails, traffic-controlling devices responsive selectively to periodic currents of different frequencies in the rails, generators located at intervals along the track and connected across the rails to feed periodic currents of different frequencies to the rails, 25 motors for actuating said generators, and a common source of direct current connected with a plurality of said motors and generators to energize the fields thereof.

2. A traffic-controlling system comprising 30 track rails, traffic-controlling devices responsive selectively to periodic currents of different frequencies in the rails, generators located at intervals along the track and connected across the rails to feed periodic currents of different frequencies to the rails, 35 motors for actuating said generators, a direct current transmission line for energizing the fields of the generators and the motors, and a periodic-current transmission line for 40 energizing the armatures of the motors.

3. A traffic-controlling system comprising track rails, traffic-controlling devices responsive selectively to periodic currents of different frequencies in the rails, generators 45 located at intervals along the track and connected across the rails to feed periodic currents of different frequencies to the rails, motors for actuating said generators, a direct current transmission line for energizing the fields of the generators and the 50 motors, and a periodic current transmission line for energizing the armatures of the motors, the two transmission lines having a conductor in common.

55 4. A traffic-controlling system comprising track rails, traffic-controlling devices responsive selectively to periodic currents of different frequencies in the rails, generators located at intervals along the track and connected across the rails to feed periodic currents of different frequencies to the rails, 60 motors for actuating said generators, a direct-current transmission line for energizing the fields of the generators and the motors, and a periodic-current transmission line for

energizing the armatures of the motors, the two transmission lines including the track rails as a common conductor.

5. A traffic-controlling system comprising track rails, traffic-controlling devices responsive selectively to periodic currents of different frequencies in the rails, generators located at intervals along the track and connected across the rails to feed periodic currents of different frequencies to the rails, 70 motors for actuating the generators, a traction current line energized with direct current, and connections between said line and the motors to energize the fields of the 75 motors.

6. A traffic-controlling system comprising track rails, traffic-controlling devices responsive selectively to periodic currents of different frequencies in the rails, generators located at intervals along the track and connected across the rails to feed periodic currents of different frequencies to the rails, 80 motors for actuating the generators, a direct traction current line, and connections between said line and the motors and generators to energize the fields thereof.

7. A traffic-controlling system comprising traffic-controlling devices, track rails, track relays controlling the traffic-controlling devices and responsive to periodic currents in the rails, said relays having fields energized by periodic currents of different frequencies, track generators located at intervals along the track and connected across the rails to feed periodic currents of different frequencies to the rails, generators located at intervals along the track and electrically independent of the track generators for energizing the fields of the relays, and means for actuating the generators.

8. A traffic-controlling system comprising traffic-controlling devices, track rails, track relays controlling the traffic-controlling devices and responsive to periodic currents in the rails, said relays having fields energized by periodic currents of different frequencies, track generators located at intervals along the track and connected across the rails to feed periodic currents of different frequencies to the rails, generators located at intervals along the track and electrically independent of each other for energizing the fields of the relays, motors for actuating the generators, and a common transmission line for energizing the motors.

9. A traffic-controlling system comprising track rails, an electrically-controlled traffic-controlling device, means for feeding to the track rails periodic currents of different frequencies at different points in the rails, a track relay responsive to periodic current in the rails located at a distance from the traffic-controlling device and provided with a field energized by periodic current to render the relay responsive selectively to peri- 130

odic current of a certain frequency in the rails, conductors constituting a line circuit connecting the track relay and the traffic-controlling device controlled thereby, a source of periodic current located at a distance from the relay, and connections between the line circuit conductors and the field of the relay and said source of periodic current, whereby the field of the relay is energized by said source and the line conductors serve as common conductors for said periodic current and for current for controlling the traffic-controlling device.

10. A traffic-controlling system comprising track rails, signals located at intervals along the track and dividing it into blocks, a signal-controlling relay connected across the rails in each block at a point in advance of the signal, the relay having a field energized by a periodic current to make the relay selectively responsive to periodic current of a certain frequency in the rails, a line circuit controlled by the relay and connecting the relay and the signal, a generator connected across the rails at a point near the signal for feeding the rails with periodic current of a certain frequency, a generator connected with the line circuit to energize the field of the magnet, said generators being designed to produce periodic currents of the same frequency, a motor connected with both generators to actuate them, a source of signal-controlling current connected in circuit with the relay and the signal through the line circuit, and means in the line circuit for separating the signal-controlling current and the periodic current by which the relay field is energized.

11. A traffic-controlling system comprising track rails, signals dividing the track into blocks and arranged with a home signal and a distant signal at the entrance of each block, means for feeding the rails with a periodic current near the entrance end of each block, the frequencies of such currents being different in successive blocks, two track relays responsive to periodic currents of different frequencies in the track rails near the center of each block, one relay being responsive selectively to current from one direction, and the other being responsive to current from the opposite direction and being arranged as a pole-changing relay, a polarized relay controlling each pair of signals selectively, a pole-changing switch actuated by each home signal, a circuit connecting each pole-changing switch with a source of current and with the field of the pole-changing track relay next in the rear, whereby the polarity of the track relay may be reversed, a circuit controlled by said track relay and connecting it with a source of current and with the polarized signal relay of the same block, whereby the track relay may control the selective action of the

signal relay, and a local signal circuit controlled by the signal relay and including a source of current and the home and distant signals, whereby one or both of the signals may be cleared by the selective operation of the signal relay.

12. A traffic-controlling system comprising track rails, traffic-controlling means responsive selectively to periodic currents of different frequencies in the rails, generators located at intervals along the track and connected across the rails to feed periodic currents of different frequencies to the rails, motors for actuating said generators, and means for actuating said motors.

13. A traffic-controlling system comprising traffic-controlling means in control of traffic along the railway, relays in control of said traffic-controlling means and each comprising two co-acting coils adapted to co-act when energized by altering currents of the same frequency, connections between the track rails and one coil of each relay, alternating current generators for energizing the other coils of the relays, alternating current motors for driving the generators, a common transmission line for energizing said motors, and means for supplying alternating currents to the track rails to energize the coils connected therewith by alternating currents corresponding in frequency to the currents in their co-acting coils.

14. A traffic-controlling system comprising traffic-controlling means arranged in control of traffic along the railway track, electro-translative devices in control of the traffic-controlling means and each comprising two coils co-active by currents of common frequency, connections between the track rails and one coil of each translative device, means for delivering alternating currents of different frequencies to the track rails at different points, an alternating current transmission line, motors impelled thereby, and alternating current generators driven by the motors and arranged to feed to the electro-translative coils not connected with the track rails currents of different frequencies corresponding to the frequencies supplied to the track rails.

15. A railway traffic-controlling system comprising traffic-controlling means in control of traffic along the railway track, electro-translative devices in control of the traffic-controlling means and each including a coil connected with the track rails and a coil co-active therewith, alternating current generators for supplying currents of different frequencies to different ones of the last said coils, alternating current motors arranged to operate said generators and all in turn operable by alternating current of one frequency different from either frequency delivered by the generator armatures, whereby it is rendered impossible to

- reproduce in the translative coils supplied by said armatures current of any frequency which may be supplied to the motors by any circumstance, a common transmission line 5 arranged to operate all of said motors by current of said one frequency adapted to operate them, and means for supplying to the track rails alternating currents of the same frequencies supplied by said generator arranged to the translative coils not connected with the track rails.
16. A railway traffic-controlling system comprising traffic-controlling means arranged to control traffic along the railway, 15 an electro-translative device in control of the traffic-controlling means and including a coil connected with the rails and a coil co-active therewith, an alternating current generator for supplying current of given frequency to the latter said coil, an alternating current motor arranged to operate said generator and in turn operatable by an alternating current of different frequency, whereby it is impossible to reproduce in the latter 20 said translative coil current of any frequency supplied to the motor, means for supplying to the motor alternating current of that frequency by which it is operatable, and means for supplying to the track rails 25 an alternating current of said given frequency supplied by the generator to the electro-translative coil not connected with the track rails.
17. A traffic-controlling system comprising track rails, traffic-controlling apparatus responsive selectively to periodic currents of different frequencies in the rails, generators located at intervals along the track and connected across the rails to feed periodic currents of different frequencies to the rails, motors for actuating said generators, and a 30 common periodic current transmission line for actuating said motors.
18. A traffic-controlling system comprising track rails, traffic-controlling means, 45 electro-translative devices in control of the traffic-controlling means and each including a coil connected with the track rails and a coacting coil, a periodic current transmission line extending along the railway, means 50 at intervals for receiving energy from the transmission line and delivering periodic current to the track rails, and electrical converting means at intervals including generator windings arranged to supply periodic 55 current to the respective electro-translative coils not connected with the track rails and including motor windings arranged to receive energy from the transmission line.
19. A traffic-controlling system comprising track rails, traffic-controlling means, 60 electro-translative devices in control of the traffic-controlling means and each including a coil connected with the track rails and a co-acting coil, a periodic current transmission line extending along the railway, means 65 at intervals for receiving energy from the transmission line and delivering periodic current to the electro-translative coils which are not connected with the track rails, and 70 electrical converting means at intervals including generator windings arranged to supply periodic current to the track rails and including motor windings arranged to receive energy from the periodic current 75 transmission line.

In testimony whereof I have affixed my signature in presence of two witnesses.
